UNITED STATES PATENT OFFICE.

ARCHIE NAULT, OF ISHPEMING, MICHIGAN.

FLUE EXPANDER AND CUTTER.

SPECIFICATION forming part of Letters Patent No. 732,313, dated June 30, 1903.

Application filed January 17, 1903. Serial No. 139,430. (No model.)

To all whom it may concern:

Be it known that I, ARCHIE NAULT, a citizen of the United States, residing at Ishpeming, in the county of Marquette and State 5 of Michigan, have invented certain new and useful Improvements in Flue Expanders and Cutters; and I do hereby declare the following to be a full, clear, and exact description of the invention, such as will enable others 10 skilled in the art to which it appertains to make and use the same.

My invention has relation to an appliance adapted for expanding a boiler-flue and also adapted for cutting said flue, whereby it may 15 be readily removed and replaced as desired; and my invention consists of certain novel features of construction and combination of parts, the preferred form whereof will be hereinafter set forth, and pointed out in the claim. 20 The prime object of my invention, among others, is to provide a combined instrument or tool which will be complete in itself and by which a flue may be very easily and expeditiously expanded or cut at or near its line of 25 union with the flue-board or boiler-wall, thereby permitting the flue to be easily withdrawn.

A further object of my invention is to provide interchangeable parts, fitting the instrument for use as an expander or flue-cutter, as 30 desired.

Other objects and advantages will be hereinafter clearly set forth, reference being had to the accompanying drawings, which are 35 made a part of this application, and in which—

Figure 1 shows a side elevation of my invention complete ready for use as a flue-cutter. Fig. 2 shows a longitudinal central section of parts thereof as presented in Fig. 1. 40 Fig. 3 shows a transverse section of my flue cutter and expander, taken on line xx of Fig. 4 and showing the removable cutters in place, while Fig. 4 shows a similar view with the cutters and also the expander-shaft removed. 45 Fig. 5 is a detail in perspective showing one of the cutter-blocks. Fig. 6 is a perspective view showing the outer end of the anchoring device employed to hold the body against relative movement with respect to the expander-shaft. 50 For convenience reference-numerals will be employed to designate the various details of my invention and accessories deemed nec-

essary to illustrate a practical application thereof to use, the same numeral applying to a similar part throughout the several views. 55

Referring to the numerals on the drawings, 1 indicates the expander-shaft, which is conical throughout its entire length, as clearly shown in Figs. 1 and 2, and is provided at its enlarged end with the preferably integral handle portion or head - section 2, having a plurality of apertures 3, through which may be extended suitable levers or rods whereby the shaft may be freely rotated in either direction. 65

The base or enlarged portion of the conical shaft 1 is provided with an angular section 4, which is preferably square in cross-section and adapted to receive the square collar 5, which is connected to or integrally formed 70 with the anchoring member 6, which is of sufficient length to extend throughout the length of the shaft 1 and is provided with the inwardly-directed neck - section 7 and the square head or collar 8, adapted to fit over 75 the squared end 9 upon the free end of the conical shaft 1, as clearly shown in Figs. 1 and 2. The head 8 is held in place upon its seat 9 by the nut 10, fitting upon the threaded terminal 11 of said conical shaft. 80

Designed to fit over the conical shaft 1 is the body portion 12, provided with a bore of sufficient size to receive the largest part of said shaft, whereby said shaft may be forced entirely home within said body portion. Said 85 body portion is provided with a plurality of openings 13 of sufficient size to loosely receive the members 14, which are provided with a rounded outer surface, as indicated by the numeral 15, and may be used with or without 90 the knife or rotary cutter 16, as preferred. If the members 14 are employed to perform the office of expanders, the rotary knife or cutter 16 will be omitted, but if designed to coöperate with said knife a suitable slit or recess is 95 formed transversely in each of the members, preferably near the central portion thereof, said slit being of sufficient width to permit the free rotation of the cutters 16, the latter being held in place by a shaft 17, as clearly 100 shown in Fig. 5. It will therefore be understood that the members 14 may be left entirely plain or provided with a knife, in accordance with the work they are to perform.

Each of the openings 18, which are designed to receive the members 14, is provided at each end with a recess 19, extending from the inner edges of the openings to a point near the outer surface of the body portion 12, the object of said recesses 19 being to loosely receive the lugs 20, which latter are designed to prevent the member 14 from casually slipping entirely out of the openings 18. It will thus be clearly apparent that the inner sides of the blocks or members 14 are thus disposed directly in contact with the peripheral face of the expander-shaft 1 and that when only the smaller end of said shaft is entered within the body portion 1 the members 14 will be entirely within the body portion, but when said shaft is forced inward the several members 14 will be simultaneously moved outward, and thereby bring their rounded surfaces or outer sides 15 into engagement with the flue, when by rotating the shaft 1 the body portion 12 will be turned, thereby bringing the members 14 successively in contact with the inner surface of the flue and expand the same to the desired extent, whereby the outer protruding end will be left in condition to be properly upset and secured in place.

It will be understood that when the instrument is being employed solely as an expander the blocks 14 will be left entirely plain on their outer surfaces or unprovided with a cutter 16. When, however, the instrument is to be employed as a flue-cutter, the plain members 14 will be replaced with similar members having rotary cutters 16, as shown in Fig. 5, and it is therefore obvious that by moving the shaft 1 inward within the body portion the several members, with their accompanying knives, will be moved outward, so as to bring said knives into engagement with the flue, whereby when the body is turned the knives will follow each other and cleanly cut the flue at the desired point.

It will be understood that the shaft 1 is not to be forced home within the body portion 12 at one operation, but to be moved gradually inward as the cutters 16 perform their office. It will be obvious that the office subserved by the member 6, which fits within the recess

21, is to cause the body portion 12 to turn with the shaft 1, whereby the knives or plurality of members 14 may be moved in engagement with the inner surface of the flue, while at the same time permitting said shaft to be 55 freely moved longitudinally within said body.

I deem it unnecessary to illustrate the rods or handle portion proper designed to be extended through the apertures 3, inasmuch as it will be readily understood that a suitable 60 rod of any desired character may be employed for this purpose.

While I have described the preferred combination and construction of parts deemed necessary in materializing my invention, I 65 wish to comprehend all such substantial equivalents and substitutes as may be considered as falling fairly within the scope thereof.

Believing that the advantages and manner of using my improved expander and cutter 70 have thus been made clearly apparent, further description is deemed unnecessary.

Having thus fully described my invention, what I claim as new, and desire to secure by Letters Patent, is—

The herein-described flue cutter and expander comprising a suitable body portion having a longitudinal central bore; a conical shaft seated in said bore; a plurality of members 14 adapted to fit loosely within apertures 80 radially disposed within said body portion whereby the inner surface of said members will be engaged and forced outward by said shaft; lugs 20 adapted to prevent the casual displacement of said members; an anchoring 85 member 6 said member having angular collars at each end adapted to take over shoulders upon said conical shaft whereby when said member is extended through a recess in the body portion 12 the said body portion is 90 held against rotation upon said shaft but permitted to move longitudinally thereon as and for the purpose set forth.

In testimony whereof I affix my signature in presence of two witnesses.

ARCHIE NAULT.
